(57) **CLAIM**
The ornamental design for a car roof ornament, as shown and described.

DESCRIPTION

FIG. 1 is a perspective view of a car roof ornament;
FIG. 2 is a front elevational view thereof, the rear elevational view being a mirror image;

FIG. 3 is a right-side elevational view thereof;

FIG. 4 is a left-side elevational view thereof;

FIG. 5 is a bottom plan view thereof with the broken line showing of rectangular LED lights not forming part of the claimed design;

FIG. 6 is a top plan view thereof; and,

FIG. 7 is a perspective view showing the present invention on top of a truck.
The broken line showing of a truck forms no part of the claimed design.
